Primary Examiner — Marie D. Fast Horse*Assistant Examiner* — Jennifer Sierra Yosinski(74) *Attorney, Agent, or Firm* — Husch Blackwell LLP(57) **CLAIM**

I claim the ornamental design for a tray, as shown and described.

DESCRIPTION

FIG. 1 is a perspective view of the tray;
 FIG. 2 is a left side elevation view of the tray;
 FIG. 3 is a right side elevation view of the tray;
 FIG. 4 is a front elevation view of the tray;
 FIG. 5 is a rear elevation view of the tray;
 FIG. 6 is a top plan view of the tray; and,
 FIG. 7 is a bottom plan view of the tray.
 Broken lines shown in the drawing views depict portions of the tray that form no part of the claimed design.

1 Claim, 7 Drawing Sheets(56)
